UNITED STATES PATENT OFFICE.

JOHN A. SPENCER, OF REVERE, MASSACHUSETTS, ASSIGNOR TO SPENCER THERMO-STAT COMPANY, OF CAMBRIDGE, MASSACHUSETTS, A CORPORATION OF MASSACHUSETTS.

ELECTRIC RIVETING MACHINE.

Application filed May 10, 1924, Serial No. 712,220. Renewed June 11, 1928.

This invention relates to metal working machines and more particularly to machines for upsetting rivets.

The principal object of the invention is to provide a rivet upsetting machine capable of performing the upsetting operation rapidly, accurately and under substantially uniform conditions of temperature and pressure.

With the above and minor objects in view the improved mechanism comprises inter alia a work supporting table or anvil which constitutes one terminal of an electrical heating circuit, a pressure applying element movable toward and from the work support or anvil and which constitutes the other terminal of said circuit, an actuator, for example a treadle, for moving the pressure applying element toward the work support, a normally open circuit breaker for determining the flow of current in said heating circuit, and connections for closing the circuit breaker substantially concomitantly with the movement of the pressure applying element into contact with work resting upon the work support.

The connections for actuating the circuit breaker are adapted to permit relative movement of the pressure applying element and circuit breaker during the actual upsetting operation so that while the circuit breaker is positioned to complete the circuit through the work the pressure applying element may complete its movement toward the work support to upset the work. The pressure applying element per se is also resiliently mounted in its support or carrier so that pressure applied to the work is determined by the compression of a spring of known strength, while the period during which the circuit is closed is automatically determined by appropriate means.

In the exemplification of the invention herein chosen for illustration, the mechanism is designed primarily for upsetting rivets disposed in circumferentially spaced holes in a thin metal disk such as is employed as the controlling element in certain types of thermostatic regulator and for this purpose the work supporting table or anvil is made circular to conform to the shape of the disk and is mounted to rotate whereby successively to

position the several rivets in the path of the pressure applying element.

One embodiment of the invention is shown by way of example in the drawings, in which:

Fig. 1 is a plan view of the mechanism, certain of the electrical connections being shown diagrammatically;

Fig. 2 is a side elevation of the mechanism with its parts positioned as at the beginning of the upsetting operation, omitting certain elements of the heating circuit;

Fig. 3 is a fragmentary vertical section showing the relative positions of the work supporting table and the pressure applying element substantially at the instant of contact of the pressure applying element with the work;

Fig. 4 is a side elevation of the parts shown in Fig. 3 but at the completion of the upsetting operation;

Fig. 5 is a fragmentary horizontal section substantially on the line 5—5 of Fig. 2;

Fig. 6 is a fragmentary vertical section substantially on the line 6—6 of Fig. 2;

Fig. 7 is a view similar to Fig. 6 but showing the parts positioned to close the circuit; and

Fig. 8 is another view similar to Fig. 6 but showing the circuit as broken and the actuating pin for the circuit breaker returning to normal position.

Referring to the drawings for a more particular description of the invention the numeral 1 designates a base or frame adapted to rest upon a bench, or which may be provided with legs or other appropriate supports not shown. A block 2 is secured by means of bolts 3 to the upper surface of the base near the right hand end of the latter as viewed in Figs. 1 and 2. This block has a vertical bore for the reception of a stem 4, projecting downwardly from the center of a circular work supporting table 5 which rests upon the upper surface of the block 2. The outer edge of this table is preferably knurled. The lower part of the bore in the block 2 is enlarged to provide a chamber for a retaining head or disk 7 having a screw-threaded stem 8

which engages a threaded axial opening in the lower end of the stem 4 of the table. The head or disk 7 is of larger diameter than the bore in the block 2 so that the table is securely retained in its operative position.

The block 2 is provided with a lateral offset portion 9 having a horizontal bore opening into the bore in the block 2 substantially in the horizontal plane of the disk 7. A ratchet block 10 slides in the bore in the offset 9 and this ratchet block is provided with a round end adapted to engage any of a series of circumferentially spaced recesses 11 in the edge of the disk 7. The ratchet block 10 is provided with a tail 12 which is encircled by a coiled spring 13 one end of which bears against the block 10 and the other against a block 14 closing the bore in the member 9. The spring pressed ratchet block 10 is thus adapted to retain the disk 7 and the table 5 in fixed position after adjustment while permitting the table to be turned to a new position at will.

In the specific embodiment of the invention herein shown the upper surface of the table is furnished with spaced depressions, corresponding in number to the recesses 11 in the disk, for the reception of the heads 15 of rivets 16 which project upwardly through suitable openings in a disk 17 which may be positioned upon the upper surface of the table by means of a pin 17^a. Insulating washers *a* and *b* may be placed on the rivet if desired at either side of the plate 17 and the upper end of the rivet is headed over onto a metallic washer *c* in the manner hereinafter described. The disk 17 with its rivets and washers thus constitutes the work to be operated upon.

Spaced brackets 18 and 19 project upwardly from the base member 1 at the opposite end of the latter from the block 2. These brackets support a pivot pin 20 providing a fulcrum for one end of a lever arm 21 which overhangs the base 1 and whose free extremity is disposed substantially above the table 5. At a point intermediate its length the arm 21 is furnished with an opening 22 for the reception of the upper end of a rigid link comprising the upper member 23 pivotally connected to the arm by a pin 24, and provided at its lower end with an axial extension 23^a. This extension telescopes in an axial bore in the lower member 23^b of the link, the latter member in turn being pivotally connected at 24^a to the intermediate part of a treadle lever 25 which is pivotally connected at 26 to a bracket 27 secured to the floor or a suitable point on the machine frame. The forward end of the treadle lever 25 is furnished with a foot engaging element 28. A coil spring encircles the adjacent ends of the link members 23 and 23^a, having its opposite ends secured to the respective members.

A spring 29 is secured at one of its ends to the treadle lever and at its opposite end to a bracket 30 mounted on the underside of the base 1. The strength of the spring 29 is such as normally to sustain the treadle link and lever arm 21 in the inoperative position indicated in Fig. 2.

To prevent unnecessary lift of the lever arm 21 a link 31 is pivotally secured thereto at the point 32 and projects down through an opening 33 in the base 1. The lower part of the opening 33 is enlarged to provide a chamber 34 within which is arranged a head 35 carried by the link, such head being of a diameter larger than that of the link 31. This head is adapted to engage the upper wall of the chamber 34 thus preventing the lever 21 from rising excessively under the action of the spring 29 but permitting the arm 21 to be depressed toward the table by the treadle.

The free extremity of the arm 21 is provided with an opening so arranged that when in operative position its axis is substantially aligned with the axis of one of the rivets, for example, the rivet 16^a, resting upon the table. At its lower end this opening is of reduced diameter providing an annular work engaging flange 36 for a purpose hereinafter described. A guide sleeve 37 is secured to the upper surface of the arm 21 coaxially with the opening in the flange 36. This sleeve is provided with an attaching flange 38 for engagement by bolts 39 passing upwardly through suitable openings in the end of the arm 21. Electrical insulating material 40 is interposed between the lower end of the sleeve 37 and the upper surface of the arm 21 and the bolts 39 are likewise insulated from the arm by suitable insulating sleeves surrounding them.

The lower end of the sleeve has an internal flange 37^a constituting a stop shoulder. A plunger 41 is arranged to slide vertically within the sleeve 37. This plunger is provided with a downwardly projecting head 42 of reduced diameter which protrudes from the lower end of sleeve 37, the flange 37^a limiting downward movement of the plunger relatively to the sleeve. The lower end of the head constitutes the pressure applying element 43. This pressure applying element is preferably of tungsten or some similar hard and difficultly fusible electrically conducting metal.

The upper end of the sleeve 37 is externally screw-threaded for the reception of a threaded adjusting cap 44. A spring 45 is interposed between the upper end of the plunger 41 and the inner surface of the cap. This spring tends to hold the plunger 41 downwardly against the stop shoulder 37^a in the position shown in Fig. 2 and the tension of the spring may be adjusted by rotating the cap.

A stem 46 projects upwardly from the

plunger 41 through a central opening in the cap 44 and is provided with means for attaching thereto one end of an electrical conductor 47 whose opposite end is grounded at 48 upon the base 1.

An intermediate portion of the conductor 47 constitutes the coarsely wound secondary coil 49 of a stepdown transformer. The finely wound primary coil 50 of this transformer is connected at one end to a conductor 51 leading from a suitable source of electrical energy. The other terminal of the primary coil is connected by a conductor 52 to one element of a circuit breaker.

15 The circuit breaker comprises a pair of substantially parallel spaced arms 53 and 54 provided with contacts 55 and 56 respectively. The arms 53 and 54 are insulated from each other and secured to a bar 57 attached to or 20 forming a part of the bracket 18, the arms 53 and 54 also being insulated from the bar 57. The conductor 52 is connected to arm 53 while a second conductor 58, corresponding to conductor 51 leads from the arm 54 25 to the source of electrical energy.

The bar 57 is provided with an opening substantially opposite to the position of the contacts 55 and 56 and this opening constitutes a guideway for a slide 59. This slide 30 is provided with a pin 60 (Fig. 6) which projects through a slot in the end of the bar 57 and which constitutes a stop to limit movement of the slide and which also prevents the slide from turning within its guide opening. 35 The slide projects from opposite ends of the bar 57, a coiled spring within a chamber in the bar 57 tending to move the slide away from the contact supporting arm 54.

The inner end of the slide is provided with 40 a cam lever 61 pivotally secured to the slide at 62 and has a spring 62^a which tends to swing the lever in a counterclockwise direction as viewed in Fig. 6. This lever thus 45 normally occupies the position shown in Fig. 6 with its free extremity bearing against the adjacent face of bar 57. Lever 61 is furnished with a forwardly projecting cam ledge or flange 61^a for a purpose hereinafter described.

50 A rod 63 is arranged to slide vertically in an opening in the base 1. This rod is furnished with a keyway 64 which is engaged by a key member 65 attached to the base by a screw 66. The upper end of the rod 63 is provided 55 with an outstanding pin 67 whose end overlies the cam ledge 61^a of the cam lever 61. The lower end of the rod 63 is bent laterally and secured to the lower end of the piston rod 70 of a dash-pot 68 secured at 69 to the base 60 1. This dash-pot is of usual construction, preferably of one-way type, opposing resistance only to downward movement of its piston, the latter being furnished with a spring, not shown, for restoring it to normal position. The lower end of the piston rod 70

is also connected to the upper end of a stiff spring 71 whose lower end is attached at 72 to the treadle lever 25.

In operating the device above described rivet heads are arranged in the several cavities in the upper surface of the work support and the apertured disk 17 is positioned upon the work support with the rivets projecting up through its apertures, the washer *a*, *b* and *c* being applied, if desired. As above described, the parts are so positioned that when the ratchet slide 10 engages one of the recesses in the disk 7, one of the rivet retaining openings of the table is axially aligned with the plunger 41.

80 The operator now places his foot upon the treadle member 28 thereby pulling the arm 21 downwardly to bring the pressure applying element 43 into contact with the rivet 16^a. Downward movement of arm 21 may continue until flange 36 engages washer *c*, thus placing spring 45 under compression. Further movement of the treadle is now permitted by the resilient connection between link members 23 and 23^b.

90 During the early part of the downward movement of lever 21, the rod 63 also moves downwardly, its movement being delayed however by the action of dash-pot 68. This movement of rod 63 causes pin 67 to bear 95 against the inclined cam ledge 61^a of lever 61, thus swinging the lever about its upper end as a fulcrum and moving slide 59 to bring contacts 55 and 56 into engagement. After contacts 55 and 56 are engaged, the pin 67 100 continues to move down along the now substantially vertical cam ledge 61^a which in the position acts as a dwell to retain the contacts engaged until pin 67 escapes from the lower end of the cam ledge, whereupon the 105 contacts immediately separate.

110 The completion of the electrical circuit through the primary winding 50 of the transformer energizes the circuit comprising the wire 47 and of which the work supporting table and the pressure applying element 43 respectively constitute the terminals. The completion of this circuit takes place substantially simultaneously with the contact of the pressure applying element 43 with the upper standing end of the rivet shank. As soon as this contact is accomplished, the circuit being completed, a heavy heating current flows 115 through the circuit of which the rivet now becomes a part, thus heating the rivet to the desired temperature for upsetting. As the spring 45 has been placed under compression, the head 43 bears with a predetermined pressure upon the work and as soon as the rivet 120 softens under the heat applied, the head 43 advances and upsets it. The pressure upon the rivet thus depends upon the strength of spring 45 and upon the distance to which head 43 initially protrudes beyond the lower 125 face of flange 36 and is unaffected by excess- 130

sive depression of the treadle, while the length of time to which the rivet is subjected to heat is also unaffected by excessive or prolonged depression of the treadle. When the treadle is released, arm 21 rises and pin 67 passes up between arm 57 and lever 61, swinging the latter, as shown in Fig. 8 until the pin arrives at its initial position, whereupon spring 62^a restores lever 61 to the position shown in Fig. 6.

The operator now turns the table 5 until the next rivet is below the pressure applying element whereupon the operation is repeated. By this means the riveting or upsetting operation may be performed with great expedition, the rivets are heated to a substantially uniform temperature and subjected to a substantially uniform pressure, even though the operator maintains his foot on the treadle for an unnecessarily long time, so that uniformity in product is secured and waste and loss of material substantially eliminated.

While the mechanism has herein been illustrated as especially designed for use in the manufacture of thermostatic control disks, it is evident that in its broader aspect it is applicable to other uses and to upsetting operations other than those which may broadly be termed "riveting."

30 I claim:

1. A machine of the class described comprising a work supporting table, a pivotally supported arm, a pressure applying element mounted upon the arm, said element being electrically insulated from the arm and movable relatively thereto, an electrical circuit of which the pressure applying element and work support respectively constitute the terminals, means normally holding the pressure applying element in spaced relation to the work support, and means for swinging the arm to move the pressure applying element into contact with work resting on the work support.

45 2. A machine of the class described comprising a horizontal work support, an arm oscillable in a vertical plane, a pressure applying element mounted upon the free end of the arm to move toward and from the work support, the pressure applying element being electrically insulated from the arm, the pressure applying element and work support constituting terminals of an electrical circuit, a treadle, and connections between the treadle and arm for swinging the latter to cause the pressure applying element to approach the work support.

3. A machine of the class described comprising a rotary work support, means for holding the work support in selected positions of angular adjustment, an oscillatory pressure applying element movable toward and from the work support, a treadle, connections between the treadle and pressure applying element for moving the latter to-

ward the work support, and means for heating work resting upon the work support while engaged by the pressure applying element.

4. A machine of the class described comprising a rotary work support, a spring 70 pressed latch for retaining said support in selected position of angular adjustment, a swinging arm, a pressure applying element mounted upon the arm and movable toward and from the work support, a treadle, an extensible link connecting the treadle to the arm, and a spring engaging the treadle and normally acting to hold the arm with its pressure applying element away from the work support.

80 5. A machine of the class described comprising a work support, a pressure applying element movable toward and from the work support, an actuator for moving the pressure applying element toward the work support 85 to apply pressure to work supported thereon, means for completing an electrical circuit to send current through the work support to the work and the pressure applying element for heating the work, lost motion connections 90 between said latter means and the actuator, additional means for limiting the pressure on the work irrespective of the velocity of motion of the actuator and a dash pot associated with said connections to time the 95 closing and opening of the circuit.

6. A machine of the class described comprising an upsetting element, a work supporting element, said elements constituting the terminals of an electrical heating circuit, a circuit breaker for determining the flow of current in said circuit comprising normally spaced contacts, and means for moving said upsetting element into engagement with the work comprising a treadle, 100 telescopically engaging members, means connecting one of said members to the treadle, and a spring connecting said members.

7. A machine of the class described comprising a work support, a pressure applying element movable toward and from the work support, an actuator for moving said element into contact with work resting upon the support, connections between the actuator and said element by which the pressure exerted 110 on the work is limited, an electrical heating circuit for heating work upon the support, a normally open circuit breaker for controlling the flow of current in said circuit, means for transmitting movement from the actuator to 115 the circuit breaker comprising resilient extensible connections and a dash pot associated with said connections to time the closing and opening of the circuit.

8. A machine of the class described comprising a work support, a pressure applying element movable toward and from the work support, an actuator for moving the pressure applying element to apply only a limited pressure to work on the work support, con- 125 130

- nections between the actuator and pressure applying element, an electrical heating circuit of which the pressure applying element and work support constitute the terminals, 5 a circuit breaker for controlling the current in said circuit, and extensible connections between the circuit breaker and actuator including a dash pot to time the closing and opening of the circuit.
- 10 9. A machine of the class described comprising a work rest, a pressure applying element, means supporting said element, an electrical circuit having the pressure applying element and work support as its terminals, a normally open circuit breaker for determining the flow of current in said circuit, a treadle for actuating the pressure applying element, and means for transmitting movement from the treadle to said element 15 comprising an elongate member pivotally connected to the treadle, a second elongate member telescopically engaging the first, resilient means opposing separation of said members, and means connecting the second 20 of said members to the supporting means for the pressure applying element.
10. A machine of the class described comprising cooperating upsetting elements constituting terminals of an electrical heating circuit, a circuit breaker for determining the flow of current in said circuit comprising normally spaced contact members, resilient means supporting one of said members, a slide for pushing said latter member toward the first member, a cam element carried by the slide, a movable pin engageable with the cam element for moving the slide, and means operating in timed relation to the operative actuation of the upsetting elements for moving the pin relatively to the cam element.
11. A machine of the class described comprising cooperating upsetting elements constituting terminals of an electrical circuit, a circuit breaker for determining the flow of current in said circuit comprising normally spaced contacts, resilient supports for the respective contacts, a slide movable into engagement with one of said supports to move it toward the other, a normally inclined cam element carried by the slide, a spring normally retaining the slide in inoperative position, a bar reciprocating in a path transverse to the path of movement of the slide, said bar having a pin engageable with the cam element of the slide to move the latter, and means operating in timed relation to the operative actuation of the upsetting elements and comprising a resiliently extensible connection for moving the reciprocating bar to cause its pin to actuate the slide.
12. A machine of the class described comprising cooperating upsetting elements constituting terminals of an electrical heating circuit, a circuit breaker for determining the flow of current in said circuit comprising nor-
- mally spaced relatively movable contacts, a slide member for moving one of said contacts into engagement with the other, a cam element upon said slide member, a part movable into engagement with said cam element for actuating the slide member, and common means for moving said part and for operatively actuating the upsetting elements.
13. A machine of the class described comprising a work support, a member movable toward and from the support, stop means for positively limiting movement of said member, an electrically insulated guide sleeve carried by said member, a plunger sliding within the guide sleeve and having a head engageable with work on the work support, a spring normally projecting one end of the plunger from the sleeve toward the work support, the plunger and work support constituting terminals of an electrical circuit, and means for moving the movable member with its guide sleeve toward the work support.
14. A machine of the class described comprising a relatively fixed work support, a swinging arm, a treadle for moving the arm toward and from the work support, and a spring pressed electrically insulated plunger constituting one terminal of an electrical circuit mounted upon the arm in a position to contact with work on the work support as the arm is swung toward the latter, the work resting upon the work support being electrically connected to the other terminal of the circuit.
15. A machine of the class described comprising a work support, an oscillatory arm having an aperture near its free extremity, a guide sleeve secured to the arm coaxially with the aperture in the arm, electrical insulation between the sleeve and arm, a plunger sliding in the sleeve having a head projecting through the aperture in the arm, a cap having threaded engagement with the free end of the guide sleeve, a spring interposed between the cap and plunger, and means for moving the arm toward and from the work support, said support and the plunger respectively constituting terminals of an electrical circuit.
16. A machine of the class described comprising an electrical circuit, a circuit controller, and means for actuating the controller comprising a slide, a lever pivotally connected to the slide, an abutment surface perpendicular to the path of movement of the slide, a spring normally holding the free end of the lever against the abutment, the lever having a normally inclined cam element, and a reciprocating part engageable with the cam element to swing the lever and move the slide.
17. A machine of the class described comprising an electrical circuit, a circuit controller comprising normally spaced contacts, a slide for moving the contacts into engagement, a cam lever mounted on the slide, an actuating pin reciprocable in a rectilinear

path and operatively engageable with the cam lever when moving in one direction to actuate the slide and passing the cam lever without operatively affecting the slide when moving 5 in the opposite direction.

18. A machine of the class described comprising a work support, a pressure applying element movable toward and from the work support, a movable carrier for the pressure applying element, a spring interposed be-

tween the carrier and said element, the carrier having a stop to limit its movement, controlling means for completing an electrical circuit through the pressure applying element and work support, and common means for operating the carrier and controlling means. 15

Signed by me at Boston, Massachusetts, this twenty-sixth day of February, 1924.

JOHN A. SPENCER.
